No. 378,872. Patented Mar. 6, 1888.

AUTOMATIC ROLL CLEANER FOR SPINNING MACHINES.

T. O. CUNNINGHAM.

(No. Model.)

UNITED STATES PATENT OFFICE.

THOMAS O. CUNNINGHAM, OF HOLYOKE, MASSACHUSETTS.

AUTOMATIC ROLL-CLEANER FOR SPINNING-MACHINES.

SPECIFICATION forming part of Letters Patent No. 378,872, dated March 6, 1888.

Application filed April 21, 1887. Serial No. 235,645. (No model.)

To all whom it may concern:

Be it known that I, THOMAS O. CUNNINGHAM, of Holyoke, in the county of Hampden and Commonwealth of Massachusetts, have invented a new and useful Automatic Roll-Cleaner for Spinning-Machines, of which the following is a specification, reference being had to the accompanying drawings, forming part thereof.

My invention relates to means for cleaning the two rolls mounted in the stationary frame or head of a spinning-machine, between which and a third gravity-roll the strands of roping pass on their way from the roping-rolls to the bobbins upon the reciprocating carriage.

As is well known, the function of these rolls is to feed forward the roping as the carriage begins its outward movement, and to hold the roping during the latter part of such movement, in order that the portion fed may be properly drawn as the carriage recedes, and in order to effectually perform this function the surface of said rolls should be free from dirt or other obstructing matter. In practice, however, it is found that the loose fibers and particles of the roping, together with the dust and other impurities contained therein, lodge upon the surface of the rolls, and, being permeated with the natural oil of the wool, gum the rolls to such an extent as to seriously impair their perfect operation, and either in part or altogether prevent the feeding and drawing of the roping. The upper roll, being readily removable from the machine, can be easily cleaned by scraping its surface with a knife or other tool; but the two lower rolls, upon which most of the obstructing matter is deposited, are mounted in bearings and can be removed only at the expenditure of considerable time and labor. It is desirable, therefore, that means shall be employed whereby these lower rolls can be cleaned without removing them from the machine.

It is the object of my invention to provide means by which said rolls can be effectually cleaned, not only without removing them from the machine, but also while the machine is in actual operation, so that no time whatever is lost by reason of the cleaning process.

To this end my invention consists in the automatic roll-cleaner, hereinafter fully described, and particularly pointed out in the claims.

Referring to the drawings, in which like letters designate like parts in the several figures, Figure 1 is a side elevation of the roll-cleaner, 55 Fig. 2 is a vertical transverse section thereof, taken upon the line xx of Fig. 1. Fig. 3 is a diagram showing in end elevation the three rolls, upon two of which the cleaner is adapted to operate, and showing in dotted lines the 60 latter applied to the rolls. Fig. 4 is an end elevation of a slightly modified form of the cleaner. Fig. 5 is a plan view of the two lower rolls with the cleaner applied thereto.

The letters A A' designate the scrapers, consisting of plates of thin sheet-steel curved to conform to the periphery of the rolls to which the cleaner is to be applied. At the bottom of their curved portion said plates are prolonged to form a flat extension, within which 70 are slots a , through which pass the bolts C, by which they are adjustably secured to the carriage B, said bolts passing through suitable holes in the carriage and receiving upon their lower ends nuts O and interposed washers N, 75 by means of which they are tightened.

The carriage B consists of a metallic plate of proper length to extend beneath both of the rolls to be cleaned, as shown by dotted lines in Fig. 3, and in width slightly less than the 80 distance between the several strands of roping, as they are arranged in the ordinary spinning-machine, which is about two inches. The carriage is provided with a centrally-located longitudinal slot, B', the function of which, as well 85 as the reason for making the carriage of the width stated, will be presently explained.

The letter D designates a bracket bent upwardly at one end, where it supports the wheel G, which, by its contact with one or the other 90 of the rolls, propels the carriage in one or the other direction longitudinally of the rolls, as hereinafter described. The wheel G is journaled upon the bolt H, which passes through a vertical slot, H', in the bracket D, as shown 95 in Fig. 4. A jam-nut, I, upon said bolt, located between the wheel and the bracket, and a tightening-nut, K, upon the opposite side of the bracket, provide for adjusting the bolt vertically within the slotted bracket, and also for 100 compensating for wear between the outer surface of the wheel and the inner surface of the head of the bolt.

The horizontal portion of bracket D extends

beneath the carriage, to which it is adjustably connected by means of the bolt F, extending downwardly through the slot in the carriage and through the said bracket. Beneath the 5 bracket the bolt F receives the handle E, which I prefer to make of wood, said handle having seated within a rectangular socket in its outer end a nut, P, whereby the turning of said handle in one direction will securely clamp the 10 bracket between the inner end of the former and the carriage, and the turning of the handle in the opposite direction will loosen said bracket, so that it can be set at any desired angle to the carriage, or can be adjusted within 15 the slot longitudinally thereof. At its inner end, where it contacts with the bracket, the handle is preferably provided with the metallic ferrule L and the washer M, the latter serving to prevent the ferrule from being forced 20 backward upon the handle.

In the diagram shown in Fig. 3 the letters S T designate the lower rolls, which are mounted in bearings in the frame of the machine, and V designates the upper roll, which is held down 25 upon the lower rolls by its own weight merely. The strands of roping a' pass from the roping-rolls (not shown) through the guide b, between the upper and lower rolls, as shown, to the bobbins c upon the reciprocating carriage. 30 (Not illustrated.) In the ordinary spinning-machine the strands of roping are arranged about two inches apart, as hereinbefore stated, and the cleaner is of such width that it can be readily passed between any two of the strands 35 in applying it to the rolls.

The operation of the cleaner above described is as follows: The scrapers A A' being adjusted by means of slots a and bolts C to the proper position to closely hug the peripheries of rolls 40 S T, as shown in Figs. 3 and 5, the handle E is loosened and bracket D is adjusted within the slot B' in the carriage, and its outer end set at such an angle to the carriage that one of the rolls S or T will be tightly clamped between 45 the wheel G and one of the scrapers. If necessary, the wheel G is also adjusted vertically within the bracket to secure this result. In Fig. 5 the wheel is shown as being adjusted to co-operate with scraper A' in clamping roll T 50 between them. These adjustments being made, the cleaner is ready to be applied to the rolls. For this purpose the operator grasps the cleaner by its handle E, and passing it between the two strands of yarn at the end of 55 the rolls places one of the scrapers against the outer side of one of the rolls S T, and by an upward pressure causes the other scraper to spring back sufficiently to pass around the outer side of the opposite roll, thereby clamping 60 said rolls between the two scrapers, as shown in Figs. 3 and 5. The same movement clamps one of the rolls, as the roll T in Fig. 5, between the wheel G and the scraper embracing 65 said roll, the rolls S and T revolving in the direction indicated by the arrows in Fig. 3. As soon as the cleaner is thus placed thereon, it begins to move longitudinally

thereof, such movement being caused by the beveled periphery of the wheel G traveling against the periphery of the roll clamped 70 between said wheel and one of the scrapers. The bracket D, being set at an angle to the carriage and consequently to the roll, causes the path of contact between the wheel and roll to follow a spiral line about the roll, 75 as indicated by the dotted line W in Fig. 5, and, by means of the friction between the wheel and roll, draws the carriage and scraper in the direction of the arrow 1 in said figure. This movement continues until the carriage 80 arrives at the bearing at the end of the rolls, when the operator grasps the handle E and withdraws the cleaner and springs it upon the next section of rolls, there being a number of such sections arranged end to end in each 85 machine, and so on until the cleaner has traversed the rolls from one end of the machine to the other. As the carriage advances, the end walls of the scrapers remove every obstruction 90 from the surface of the rolls and leave them perfectly clean. The changes from one section of rolls to the next one are made by the operator while the carriage pauses at the end of its inward movement, and, being almost instantly performed, do not interfere with his 95 other duties. It will thus be seen that the cleaner automatically performs its function while the machine is in actual operation.

By reference to Fig. 3 it will be observed that the scrapers do not come in contact with 100 the strands of roping at the rear side nor with the strands of twisted yarn at the front side of the rolls, and that consequently the cleaner does not interfere in any manner with the operation of the rolls.

The speed of the movement of the carriage can be regulated by varying the angle between the bracket D and the carriage, and its direction can be reversed by adjusting the wheel G to contact with the opposite roll. The steel 110 scrapers A A' are preferably tempered to increase their durability, and the heads of bolts C, against which the rolls revolve, are case-hardened.

In Fig. 4 I have shown a slight modification 115 in the construction of the scrapers, in which scraper A is removed and a scraper, R, secured to the carriage in its place, said scraper R being constructed to embrace both sides of the roll S. This latter construction is useful 120 only in machines running at a high speed, when the operator might not have time to apply the cleaner upon both rolls at one pause of the carriage. With the modified construction he could apply the scraper R to the front 125 roll at one pause of the carriage, which would support the cleaner until the next inward movement, when he could spring the scraper A' upon the rear roll.

For all machines running at the ordinary 130 speed, however, the operator has ample time to manipulate the cleaner, as first described; and I prefer that construction.

The roll-cleaner as thus constructed is sim-

ple and inexpensive and yet effective in operation. While I have described its function as being to clean the rolls of spinning-machines, it is obvious that it would be equally effective 5 for the purpose of cleaning rolls of other machines.

Various modifications can be made in the details of construction within the spirit of my invention—as, for instance, adapting the 10 cleaner to operate upon a single roll, instead of upon two, as described, which could be done by omitting the scraper A' in Fig. 4 altogether, and arranging a bar or guide, as shown by dotted lines at m in said figure, against which 15 the handle E could travel, to retain the propelling-wheel in contact with the roll.

Having thus fully described my invention, what I claim, and desire to secure by Letters Patent, is—

20 1. A cleaner for the rolls of spinning and other machines, consisting of a carriage having secured thereto curved scrapers adapted to partially embrace two of the rolls to be cleaned, and having a propelling-wheel, and means, substantially as described, for holding said wheel 25 in contact with either of said rolls at an angle thereto, combined and operating substantially as set forth, whereby when said wheel is in contact with one of said rolls the carriage 30 will be moved longitudinally thereof in one direction, and when it is in contact with the other of said rolls the carriage will be moved in the opposite direction.

2. In a cleaner for the rolls of spinning and 35 other machines, the combination of a carriage having curved scrapers adjustably secured thereto adapted to partially embrace the rolls to be cleaned, with a propelling-wheel, a bracket having at one end a bearing for said 40 wheel and connected at the other end to the carriage, and means, substantially as described, for adjusting said bracket at any desired angle to the carriage, substantially as and for the purpose set forth.

3. The combination, with the carriage B, having the curved scrapers A A' secured thereto, of the bracket D, the wheel G, mounted in a bearing at its outer end, and a bolt and nut connecting the inner end of said bracket to the carriage, whereby said bracket may be secured at different angles to the carriage, substantially as and for the purpose described. 45

4. The combination of carriage B, scrapers A A', bracket D, wheel G, and handle E, having the fixed nut P, with bolt F, connecting 55 said carriage, bracket, and handle, arranged and operating substantially as set forth.

5. The combination of the carriage B, having the centrally-disposed slot, and having the scrapers A A' adjustably secured thereto, of 60 bracket D, wheel G, handle E, bolt F, passing through the slot in the carriage and through said bracket and handle, and nut P, seated within a socket in the handle, substantially as set forth. 65

6. The combination, with the carriage having the scrapers A A' secured thereto, of the bracket D, having the vertical slotted outer end, as shown, wheel G, bolt H, passing through the center of said wheel and through 70 the slot in the bracket, nuts I and K upon said bolt, and a nut and bolt securing the inner end of said bracket to the carriage, whereby provision is made for adjusting said wheel G both vertically and laterally with respect 75 to the carriage, substantially as set forth.

7. The combination, with the carriage and propelling-wheel arranged and operating substantially as shown and described, of the scrapers A A', each having a slotted horizontal extension, as shown, bolts C, passing through the slots therein and through the carriage, and nuts O, substantially as set forth. 80
